UNITED STATES PATENT OFFICE.

HENRY C. WALKER, OF NEWTON, MASSACHUSETTS, ASSIGNOR TO WALKER-LONGFELLOW COMPANY, OF BOSTON, MASSACHUSETTS, A CORPORATION OF MAINE.

BOX.

993,330.

Specification of Letters Patent. Patented May 23, 1911.

Application filed December 27, 1910. Serial No. 599,476.

To all whom it may concern:

Be it known that I, HENRY C. WALKER, a citizen of the United States, residing at Newton, in the county of Middlesex and 5 State of Massachusetts, have invented new and useful Improvements in Boxes, of which the following is a specification.

My invention is a combined calendar and stationery or stamp or memorandum box, 10 made up out of two boxes or receptacles combined together by a hinged cover piece.

In the drawings: Figure 1 is a perspective view of my combination box open; Fig. 2 is a central longitudinal section of Fig. 1; 15 Fig. 3 is a perspective view of my combination box closed; Fig. 4 is a perspective view of a part of the side wall, *a*, showing the slot *a x*.

Receptacles for the holding of various 20 articles, such as stamps, rubber bands, stationery or the like have been used heretofore, being either uncovered or covered by a cover of ordinary type. In my new box the main box may be made with one or more 25 compartments and with manipulating slots in the sides through which the fingers may easily reach the contents of any compartment to extract the contents thereof.

To one end of the open side of the main 30 box is hinged a cover piece which is itself hinged at its other end to another box, one side of which is open. The two hinges work in opposite directions, that is to say, the hinge between the main box and the cover 35 portion is arranged to permit the cover to swing upward while the hinge between the cover and the supplementary box opens in such a way that the ends of the cover and the supplementary box which are hinged to- 40 gether may be lifted up until the under side of the cover and the supplementary box approach one another.

In the drawings *A* is the main box; *a* and *a'* the side and end walls respectively of the 45 main box; *a²* are the slots to permit access to the edges of papers or the like within the box; *b* is the lid; *C* is the supplementary box, the lid or cover *b* being hinged to the box *A* at the line *x* and the supplementary 50 box *C* being hinged to the lid or cover at line *z*, any suitable structure capable of acting as a hinge connection between the parts being employed.

The supplementary box *C* is open upon one side, at *d*, and has an aperture *d'* upon one side through which may be inserted a number of calendar cards which may be shifted from month to month and the calendars, printed upon the calendar cards, viewed through the opening *d*. In operation the cover *b* is turned upward as shown in Fig. 1 carrying up with it one side of calendar box *C*, the lower side of the calendar box *C* drawing along the upper edges of walls *a* until the free edges of the calendar 60 box drops into notches *a x* in the side walls, *a*, of the box, *A*, to sustain the calendar box and cover in the open position. In this position the main box *A* is open for holding and delivering articles while the calendar 65 cards are held in position in calendar box *C* for observation through the aperture *d*. By merely lifting the ends of the calendar box out of the notches, the cover will close itself by gravity, a wall *b'* at one end of the cover 70 *b* closing the slot *d'* in the side of the calendar box so that the calendar cards cannot work out of the calendar box. In the best 75 form of my device the front or upper side of the calendar box projects and laps over the end of the cover piece *b* when the cover and calendar box are closed upon top of the main box *A* and this extension, *d²*, may be used as a handle for lifting the cover by swinging it upward, the application of such 80 force resulting in throwing the cover *b* in one direction and the calendar box in another direction until they assume the position shown in Figs. 1 and 2.

I claim:

1. The double box, made up of a body box; a cover piece hinged thereto to permit the cover piece to be lifted and a second box hinged to the cover piece to permit it to fold down toward the under side of the cover piece, and serving as a cover for part of the body box, when in closed position.

2. The double box, made up of a body box; a cover piece hinged thereto to permit the cover piece to be lifted and a second box hinged to the cover piece to permit it to fold down toward the under side of the cover piece and having an aperture through its upper side to expose the contents thereof.

3. The double box made up of a body box; 105 a cover piece hinged thereto to permit the

cover to be lifted and a second box hinged to the cover piece to permit it to fold down toward the under side of the cover piece and having an aperture through its upper 5 side to expose the contents thereof, and a second aperture adjacent the cover piece hinge for the insertion of cards into the box, the cover piece having a wall adapted to

close the second aperture when the double box is closed.

10

Signed by me at Boston, Massachusetts,
this 21st day of December, 1910.

HENRY C. WALKER.
